(57) **CLAIM**

The ornamental design for a camera mount for a rearview mirror, as shown and described.

DESCRIPTION

FIG. 1 is a rear perspective view of a camera mount for a rearview mirror showing my new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1; and,

FIG. 8 is a rear perspective view of FIG. 1 shown in use.

The broken lines in FIGS. 1 through 8 are environmental structure only and form no part of the claimed design.
